(57) **CLAIM**

The ornamental design for a controller for digital audio player, as shown and described.

DESCRIPTION

FIG. 1 is a top-right-front perspective view showing the controller for digital audio player of my design; FIG. 2 is a bottom-left-rear perspective view thereof;

FIG. 3 is a front view thereof;

FIG. 4 is a rear view thereof;

FIG. 5 is a left-side view thereof;

FIG. 6 is a right-side view thereof;

FIG. 7 is top view thereof; and,

FIG. 8 is bottom view thereof.

The broken lines depict portions of the controller for digital audio player that form no part of the claimed design.

1 Claim, 8 Drawing Sheets
